UNITED STATES PATENT OFFICE

HARRY K. BERGMAN, OF SHILLINGTON, PENNSYLVANIA, ASSIGNOR TO HEMPHILL COMPANY, OF CENTRAL FALLS, RHODE ISLAND, A CORPORATION OF MASSACHUSETTS

MECHANISM FOR FORMING CLOCKED, FLOATED-THREAD HOSIERY

Application filed March 16, 1928. Serial No. 262,275.

This invention particularly relates to mechanism for forming clocked stockings wherein the clocking thread or threads is or are floated from clocking area to clocking area. Some of the features and combinations of my invention may, however, be used in other relations.

In order that the principle of the invention may be readily understood, I have disclosed a single embodiment thereof in the accompanying drawings, wherein—

Fig. 1 is a side elevation of hosiery having clocking areas formed by the mechanism of my invention;

Fig. 2 is a similar view but representing a different design of clocking;

Fig. 3 is a detail upon an enlarged scale, and showing the loops, of the clocking design of Fig. 1;

Fig. 3^a is a diagrammatic representation constituting a horizontal section taken through the hose or stocking and representing the knitting in of the clocking thread or threads and the floating thereof between the sides of the hose or stocking;

Fig. 4 is a front elevation of a circular knitting machine for knitting seamless hosiery, to which my invention may be employed;

Fig. 4^a is a side elevation of a few links of the pattern chain employed in making the design of Fig. 1;

Fig. 4^b is a similar view, but of links employed in making the design of Fig. 2;

Fig. 5 is a left hand elevation of the mechanism shown in Fig. 4;

Fig. 6 is a plan view of the knitting cam block and certain of the cams and co-acting parts, with parts in section;

Fig. 7 is an inside elevation with parts in section showing the knitting cams and the needles thereat;

Fig. 8 is a somewhat diagrammatic representation of the circular series of needles to indicate the different lengths of butts, no at-

tempt being made to indicate accurately the total number of needles, but accurately indicating the number of so-called design needles employed in making the clocked hose of Fig. 1;

Fig. 9 is a perspective view of a few of the needles and indicating the different lengths of butts;

Fig. 10 is a plan view of the inner ends of certain of the cams and showing the top center cam moved outwardly one step so as to make one (double) stripe of a clocking area, the so-called auxiliary cam being wholly in;

Fig. 11 is a similar view but representing the top center cam moved one step further out so as to make three stripes of the clocking area;

Fig. 12 is a similar view representing said top center cam moved out one more step so as to make five stripes of the clocking area;

Fig. 13 is a similar view representing the top center cam all the way in, no clocking being made, and the auxiliary cam moved out for heel and toe work;

Fig. 14 is a rear elevation of the machine showing the cam block and part of the cylinder with means for moving the auxiliary cam;

Fig. 15 is a plan view, with parts broken away, to show the thread or yarn fingers preferably used; and

Fig. 16 is a transverse central section showing one of the designing yarn or thread fingers.

The primary purpose of the invention is the provision of mechanism for making clocked hosiery of the character disclosed in the patent to Clarence H. Taubel, No. 1,619,788, dated March 1, 1927, and by the method there disclosed. Certain of the combinations of mechanism may in some cases be employed in different relation, and my invention is not limited in this respect excepting as hereinafter claimed. In order to make a clear presentation of the invention I have

selected as one embodiment of my invention that herein disclosed, and I shall without limiting myself thereto specifically describe the same as for the purpose of making a stocking of the character shown in said patent to Taubel, No. 1,619,788.

In Fig. 1, and upon an enlarged scale in Fig. 3, wherein a part only of a hose or stocking is shown, I have represented at 1 a circular or seamless knit hose or stocking which may be of any desired length, being either a woman's stocking or, as herein shown, provided with a ribbed top 2 in a manner generally characteristic of a man's hose. Such stocking is provided with a heel 3 and a toe 4 made by a narrowing and widening operation, and desirably with the introduction of an additional yarn or thread or the substitution of another yarn or thread in the making of such heel or toe, in a manner not necessary more fully to describe.

The hose or stocking may be knit upon any suitable circular knitting machine, as, for example, a Banner machine of the general type disclosed in the patent to Joshua B. Hemphill, No. 933,443. While obviously the hose or stocking and the clocking thread or threads may be of any desired colors, I will, for convenience of description only, refer to the body thread or yarn of the hose or stocking as white in color. Such thread or yarn is introduced as the main or body thread in usual manner, not necessary to describe. At any desired point, as, for example, a slight distance below the rib top, if the latter be provided, or at the boot or ankle portion of a woman's stocking, I introduce the clocking thread or one of a plurality of clocking threads. In the design or example represented in Fig. 1, I have introduced two differently colored threads, herein for convenience represented as A and B, said threads being fed in succession or otherwise according to the dictates of the pattern control. In the present instance, I have represented the clocking thread A as first introduced so as to make a single stripe, here shown as two wales in width. Immediately therebelow are shown three stripes which may be of the yarn B or the yarn A, or both yarns A and B. Immediately therebelow, I have shown five stripes which likewise may be of any color or combination of colors; therebelow I show three stripes, and next below the same one stripe, after which the described design is repeated as desired. I have here shown the same extending into the foot. In Fig. 3, I have diagrammatically indicated the clocking threads A and B as floated across the fabric in the manner described in the said Taubel patent.

In Fig. 2, I have represented a different design wherein two clocking threads A and B of different colors are employed. Said design, which need not be described in de-

tail, as indicated at 5, it being merely necessary to state that whereas in the making of the design of Fig. 1, separate links are employed to make the one stripe, the three stripe and the five stripe areas, as indicated at 6, 7 and 8, in making the design of Fig. 2 I employ sets of two stepped links indicated at 9, 10, and hereinafter more fully referred to.

For purposes of explanation merely, I have represented my invention as applied to a circular or seamless hosiery knitting machine of the well known Banner type, but it is to be understood that the invention may be applied equally well to other types of circular knitting machines.

Referring now to Figs. 4 to 16, and first to Figs. 4 and 5, the framing of the machine is indicated at 11, and at 12 is indicated a table or base plate surmounting the frame. The needle carrier or cylinder 13 is journaled to rotate in the table 12 and is driven in the usual manner from the main drive shaft 14 having thereon suitable pulleys, such, for example, as loose pulley 15, and fast pulleys 16 and 16' for imparting different speeds to the needle carrier during reciprocating and rotary knitting. Surrounding the needle carrier 13 is a cam ring support or annular plate 17 whereon are mounted various cams for controlling the movements of the knitting instruments. The member 17 may be of the usual construction and need not be further described. The knitting needles 19 (generally indicated in Fig. 4) may be of any desired type and are indicated as latch needles arranged in grooves in the needle carrier 13 in usual manner to be reciprocated vertically therein by a set of knitting cams mounted upon a block 20, indicated in Fig. 6 and elsewhere. Said cams include two main, oppositely positioned stitch cams 21, 22 performing the functions of the corresponding cams in the usual Banner machines, the central cam 23, and two additional cams to which and the movements whereof my invention is more particularly directed. Above the central cam 23 is a top guide cam 24 which, in the present instance, instead of being symmetrically positioned, as, for example, in the patent to Lawson, No. 1,433,386, October 24, 1922, is positioned off center or non-symmetrically. At the left hand side of said top guide cam 24, viewing Fig. 7, is an auxiliary cam 25. These cams are shown upon an enlarged scale in Figs. 6 and 10 to 13, and in Figs. 10 to 13 the different positions of the said two cams 24 and 25 are clearly indicated. Before referring to the several positions of these cams I will refer to the character of the needles employed in the machine herein selected for disclosure of my invention.

Referring to Figs. 8 and 9, it will be observed that in the present machine I have disclosed five different lengths of butts. The so-called long butt needles in the selected em-

bodiment of my invention are indicated at 26 and they comprise one half the entire circle of needles. The other half circle of the needles is mainly made up of a set of needles 27, the butts whereof are herein referred to as 5 special short butts, said butts being longer than those of the usual short needles of the Banner machine. In addition, I have in this embodiment of the invention disclosed three 10 different lengths of butts of so-called designing needles. In the present instance, there are six of these designing needles at each of two opposite sides or parts of the needle circle.

15 In Fig. 8, I have represented at the top of the figure and at the bottom thereof the longest-length-butt designing needle at 28, there being a single such needle, here shown positioned next to the last needle of the long butt 20 series 26. Next to said needle 28 is a single one of the special short needles 27, and next thereto at the right is a single designing needle 29, the butt whereof is shorter than the butt of the needle 28. Next thereto on the 25 right is a single special short needle 27, and next thereto on the right are two designing needles 30 of shorter length butt than the needles 29. Next thereto on the right is a single special short needle 27 and next thereto on the right is a needle 29 immediately beyond which is a special short needle 27, next to which is a needle 28, and thereafter follows the large group of special short needles 27. It is to be understood that the needles 27, 30 wherever positioned, receive merely the main thread or yarn, and that the clocking threads or yarns are received upon the designing needles 28, 29, 30, which, of course, also receive the main thread or yarn. The long butt 35 needles 26 receive only the main thread or yarn.

In accordance with my invention and in order, in the disclosed embodiment thereof, to move the cams 24, 25 positively so that a 40 clocked stocking made by the float thread process shall result, I provide for certain movements of said cams 24, 25. Said cam 25, herein termed an auxiliary cam, has only two 45 positions, namely, the in position illustrated in Fig. 10 and occupied by it at all times excepting during heel and toe work, and the out position which is represented in Fig. 13, such position being occupied for and during 50 heel and toe work. In the position of the auxiliary cam 25 shown in Fig. 10, all of the needles engage by their butts the said auxiliary cam and are moved down thereby to bring them under the influence of the stitch cam 21. When said auxiliary cam 25 is in its 55 out position, none of the needle butts is engaged thereby; that is to say, said auxiliary cam 25 does not function during the knitting of the heel and toe. The means for operating 60 said auxiliary cam 25 will be hereinafter 65 described.

The top guide cam 24 has four positions respectively indicated in Figs. 10, 11, 12 and 70 13. The number of these positions is determined by the number of different lengths of the designing needles, which in this embodiment of the invention is three.

Therefore in Fig. 10 the said cam 24 is represented as in a position to move downwardly all needles excepting the shortest butt 75 designing needles 30. In the position shown in Fig. 11, said cam 24 has been moved outwardly an additional step so as to permit to pass thereby without moving downward, not only the shortest butt needles 30, but the next shortest length butt needles 29. In the position shown in Fig. 12, the cam 24 has been moved outwardly another step so that it permits to pass thereby without downward movement not only the shortest butt needles 30 and the next shortest butt needle 29, but 80 also the needles 28 which are the longest butt needles of the designing needles. In the present embodiment of the invention, when the cam 24 is in the position shown in Fig. 10 a clocking portion or area of a single stripe 85 only is made; when in the position shown in Fig. 11 a clocking area of three stripes is made, and when in the position shown in Fig. 12 a clocking area of five stripes is made. When the cam 24 is moved into the position 90 shown in Fig. 13, all needles are moved downwardly by it and hence no clocking stripe is made.

In order to move the cam 24 into the several 95 positions any suitable means may be employed. I have represented said cam as having therein lengthwise extending slots 31 to receive bolts or screws 32 extending into the cam block 20. In order to move the said cam 24 in and out so as to position it as described, I have provided a link 33 secured by 100 a screw 34 to the top face of the said cam 24. Said link 33 is bent as shown and near its outer end is pivotally connected at 35 to an arm of a bell crank lever 36 pivoted at 37, 105 and to the outer end of which at 38 is pivotally connected an end of an upright rod 39. Said rod has thereon a collar 40 between 110 which and the point of pivotal connection 38 is a coil spring 41 tending to move said rod 39 downward. At its lower end said rod 39 is pivotally connected at 42 to one arm of a 115 rocking lever 43 pivoted to the framing of the machine and having a cam arm 44 resting upon the links of the pattern chain 45. The 120 said pattern chain has among other links, the links 6, 7, 8, 7 and 6, shown in Fig. 4^a, the function of which is to move said cam 24 positively into the several positions hereinbefore referred to for the purpose of providing clocking areas at the proper points. The auxiliary cam 25, as stated, has but two 125 positions. Said cam is as shown in Fig. 6 provided with two slots 46 through which extend screws 47 from the cam blocks so that the 130

said cam 25 may be moved in and out. In order to move the said cam, any suitable means may be provided, but herein for the purpose I have provided the following means, shown most clearly in Figs. 5, 6 and 14. To the said cam is secured by a bolt 48 a link 49 which, as shown in Fig. 14, is pivotally connected at 50 to a lever 51 pivoted at 52 upon a bracket or part rising from the bed plate 10 of the machine. The lever 51 is of general right angled form and to its outer end is connected at 54 a coil spring 55, the upper end of which is connected at 56 to an arm 57 fixedly secured to the bracket 53 by screws 15 or bolts 58. The spring 55 tends to move the auxiliary cam 25 outward. Such outward movement is, however, resisted by a lever 59 pivoted at 60 upon a bracket upon the bed plate as shown in Fig. 14. Said lever 59 has 20 a bent end 62 resting upon the horizontal portion of the lever 51 in a sliding relation. It is evident that when the longer arm 63 of the lever 59 is moved downwardly, the lever 51 is moved into such position as positively to move the auxiliary cam 25 inward. 25 In order to impart the desired movements to said lever 59, the arm 64 thereof is pivotally connected at 65 to the upper end of an upright rod or link 66. As shown in Fig. 5, 30 said rod 66 has secured thereto a collar 67 to which is connected one end of a coil spring 68, the upper end thereof being connected at 69 to the framing of the machine. Pivotally connected at the lower end of the rod or link 35 66 at 70 is a lever 71 pivoted at 72 upon the framing and having an arm 73 provided with a toe or end 74 resting upon a special cam shown at 75 as secured upon the main pattern shaft 76. The toe 74 of the said lever 71 is 40 held in engagement with the surface of the cam 75 by the coiled spring 68, and so long as the lever 71 is in the position shown in Fig. 5 the cam 25 remains in its position shown in Figs. 10, 11, 12. The said cam 75 is provided with elevations 77 and 78, the former being for the toe and the latter for the heel. 45 When the toe 74 of the lever 71 rides upon either projection 77 or 78, the said cam 25 is moved outward into the position shown in Fig. 13. Said cam 25 is in its position during the knitting of the leg and the foot.

It is evident that the precise movements and the timing of the movements of the cam 24 depend upon the form of links used and the arrangement thereof upon the pattern chain. When links are employed, such as shown in Fig. 4^a, each special link 6, 7, 8 controls twelve courses. In that form of link shown in Fig. 4^b each special link 9, 10 has 50 three step parts 79, 80, 81, each of which controls four courses.

It is evident from the foregoing description and from Fig. 7 that the designing needles take the clocking or additional thread 55 or threads at a slightly higher level than the

needles take the main knitting thread or yarn. In order to provide for the proper feeding of the clocking thread or threads, I preferably provide special thread fingers shown in Figs. 15 and 16. The fingers are 70 generally similar to those of the Banner machine, and the entire group of fingers is represented as pivoted at 82 upon the latch ring 82'. In the present instance, I have represented four thread fingers, that indicated at 75 83 supplying the regular thread or yarn for the leg and the foot, that indicated at 84 supplying another thread or yarn for the heel and the toe, and the fingers 85 and 86 supplying the clocking threads. The finger 86 is 80 represented in Fig. 16. It is provided with a passage 87 extending therethrough and at its inner face with a short tube 88 which extends close to the stem of the needles generally indicated at 19, so as to make certain 85 that such thread is received thereby.

It will be understood from the foregoing description that I have provided for the positive control through the agency of the knitting mechanism of the top guard cam 24 90 and the auxiliary cam 25. I am aware of the fact that it has heretofore been proposed, as in the patent to Robinson No. 1,291,155, to employ two cams, one of which is engaged and moved by needle butts of one length and 95 the other of which is engaged and moved by needle butts of another length, and hence in a non-positive manner, said cams being primarily intended for use in making a parallel sided high splice. By my invention, however, the two cams 24, 25 are positively controlled by the knitting mechanism, and are not moved by the needles. 100

Having thus described one illustrative embodiment of my invention, I desire it to be 105 understood that although specific terms are employed, they are used in a generic and descriptive sense and not for purposes of limitation, the scope of the invention being set forth in the following claims.

Claims:

1. In a circular, independent needle, hosiery knitting machine attachment for making opposite so-called clocking areas composed of an additional thread or threads, said areas connected together by float portions of said threads, which float portions extend uninterruptedly from one of said clocking areas to the other, and for which needles having contrasting butts are provided, a two-part top guide cam at and constituting a part of the stitch cam set, and mechanical connections for automatically and separately moving each part of said two-part top guide cam so as to render said two parts active or non-active upon certain needles, according to the contrasting butt formation. 115

2. In a circular, independent needle, hosiery knitting machine attachment for making opposite so-called clocking areas com- 120

- posed of an additional thread or threads, said areas connected together by float portions of said threads, which float portions extend uninterruptedly from one of said clocking areas to the other, and for which needles having contrasting butts are provided, a two-part top guide cam at and constituting a part of the stitch cam set, one of said cam parts being substantially centrally arranged with respect to the stitch cams and the other of said cam parts being arranged at one side of the first mentioned part, both of said cam parts being restrained from movement in a direction circumferentially of the needle circle, and independent connections from a moving part of the machine for positively moving both of said cam parts out and in, in accordance with the shape of needle butts upon which said cams are to operate.
- 5 3. In a circular, independent needle, hosiery knitting machine attachment for making opposite so-called clocking areas composed of an additional thread or threads, said areas connected together by float portions of said threads, which float portions extend uninterruptedly from one of said clocking areas to the other, and for which needles having contrasting butts are provided, a two-part top guide cam at and constituting a part of the stitch cam set, one of said cam parts being substantially centrally arranged with respect to the stitch cams and the other of said cam parts being arranged at one side of the first mentioned part, both of said cam parts being restrained from movement in a direction circumferentially of the needle circle, the pattern shaft, connections therefrom to the second mentioned cam part for rendering said cam part inactive during heel and toe work and other connections extending from said pattern shaft to the first mentioned cam part to move said first mentioned cam part out and in in a series of three steps each, corresponding to the lengths of the needle butts to be acted upon by said first mentioned cam part.
- 10 4. In a circular, independent needle, hosiery knitting machine attachment for making opposite so-called clocking areas composed of an additional thread or threads, said areas connected together by float portions of said threads, which float portions extend uninterruptedly from one of said clocking areas to the other, and for which needles having contrasting butts are provided, a two-part top guide cam at and constituting a part of the stitch cam set, one of said cam parts being substantially centrally arranged with respect to the stitch cams and the other of said cam parts being arranged at one side of the first mentioned part, both of said cam parts being restrained from movement in a direction circumferentially of the needle circle, the pattern shaft and independent connections from said shaft to said two cam parts respectively to move them out and in according to the length of the needle butts upon which they are to operate.
- 15 5. In a circular, independent needle, hosiery knitting machine attachment for making opposite so-called clocking areas composed of an additional thread or threads, said areas connected together by float portions of said threads, which float portions extend uninterruptedly from one of said clocking areas to the other, and for which needles having contrasting butts are provided, a two-part top guide cam at and constituting a part of the stitch cam set, one of said cam parts being substantially centrally arranged with respect to the stitch cams and the other of said cam parts being arranged at one side of the first mentioned part, both of said cam parts being restrained from movement in a direction circumferentially of the needle circle, the pattern shaft, a pattern member thereon having cam formations for moving said second mentioned cam part out of action during heel and toe work, mechanical connections from said pattern member to said second mentioned cam part; the pattern chain upon said pattern shaft having special link formations for controlling the in and out positions of said first mentioned cam part and connections from said special link formations to said first mentioned cam part for moving the latter out and in in accordance with the length of needle butts to be acted upon by said first mentioned cam part.
- 20 6. In a circular, independent needle, hosiery knitting machine attachment for making opposite so-called clocking areas composed of an additional thread or threads, said areas connected together by float portions of said threads, which float portions extend uninterruptedly from one of said clocking areas to the other, and for which needles having contrasting butts are provided, a two-part top guide cam at and constituting a part of the stitch cam set, one of said cam parts being substantially centrally arranged with respect to the stitch cams and the other of said cam parts being arranged at one side of the first mentioned part, both of said cam parts being restrained from movement in a direction circumferentially of the needle circle, the pattern shaft, connections therefrom to the second mentioned cam part for rendering said cam part inactive during heel and toe work and other connections extending from said pattern shaft to the first mentioned cam part to move said first mentioned cam part out and in in accordance with the length of needle butts to be acted upon by said first mentioned cam part.
- 25 7. In a circular, independent needle, hosiery knitting machine attachment for making opposite so-called clocking areas composed of an additional thread or threads,

- said areas connected together by float portions of said threads, which float portions extend uninterruptedly from one of said clocking areas to the other, and for which needles having contrasting butts are provided, a two-part top guide cam at and constituting a part of the stitch cam set, one of said parts being substantially centrally arranged with respect to the stitch cams and the other of said cam parts being arranged at one side of the first mentioned part, both of said cam parts being restrained from movement in a direction circumferentially of the needle circle, and independent connections from a moving part of the machine for positively moving both of said cam parts out and in in accordance with the shape of needle butts upon which said cams are to operate. 70
